M. D. RIKER

JACK

Filed March 25, 1920

Inventor
Malcolm D. Riker
By his Attorney
E. W. Marshall

UNITED STATES PATENT OFFICE.

MALCOLM D. RIKER, OF DOVER, NEW JERSEY, ASSIGNOR TO MCKIERNAN-TERRY DRILL COMPANY, OF DOVER, NEW JERSEY, A CORPORATION OF NEW JERSEY.

JACK.

Application filed March 25, 1920. Serial No. 368,651.

To all whom it may concern:

Be it known that I, MALCOLM D. RIKER, a citizen of the United States of America, and a resident of Dover, county of Morris, 5 and State of New Jersey, have invented certain new and useful Improvements in Jacks, of which the following is a specification.

The objects of the present invention are to provide a lifting jack of particularly 10 light, compact, simple and powerful construction and especially suited to automobile needs.

The invention involves a number of novel 15 features of construction, combinations and arrangements of parts, as will be hereinafter disclosed in detail.

In the drawing accompanying and forming 20 a part of this specification, I have illustrated the invention embodied in one of its simple, practical forms, but wish it understood that the structure may be modified without departure from the true spirit and scope of the invention.

In the drawing referred to, Figure 1 is a 25 vertical sectional view of the complete jack.

Figure 2 is a view looking at the right hand side of Figure 1, with portions of the jack broken away and shown in section.

Figure 3 is a horizontal sectional view 30 taken on substantially the plane of line 3—3 of Figure 1.

Figure 4 is another horizontal sectional view taken on substantially the plane of line 4—4 of Figure 2.

One of the special features of the invention is the making of the supporting post and the extensible sleeve or column of two sections of commercial cylindrical tubing 35 cut to the proper length and arranged to slide, one over the other. The inner section of tubing, which constitutes the tubular supporting post is designated 5 and the surrounding sleeve is designated 6. The supporting post is provided with a suitable base, such as I have indicated at 7 and to which the post is shown as secured by means of a welded joint 8. The sleeve is non-rotatably but slidably engaged on the post by indenting opposite side portions at the lower end thereof, as indicated at 9, to provide flattened parts sliding over oppositely indented flattened side portions 10 of the post which extend throughout the length thereof.

The sleeve carries the lifting head 11, which is shown as set in the upper end of the 55 sleeve and secured thereto by the welded joint at 12. The sleeve may also be provided with an outstanding foot or step 13 for engagement beneath relatively low objects, or in places where the lifting head cannot be 60 used.

The sleeve is operated by a screw 14 having a bearing in the nut 15.

This nut is supported in the upper end 65 of the tubular post and is shown as non-rotatably engaged therein by having the radial webs 16 engaging in the top of the post and bearing against the cylindrical inner surfaces of the post at opposite sides of the flattened portions thereof (Fig. 3). This 70 nut furthermore is shown as fixedly secured in the end of the post by means of a portion 17 of the wall of the post indented into a pocket 18 formed in one of the webs of the nut, said wall being thus indented over the shoulder provided by the pocket in the nut by means of a suitable tool inserted through an opening 19 provided in the outer sleeve.

The screw has a rotating connection with the head and is also provided with means by which it may be turned one way or the other. The means illustrated for this purpose comprises a bevel pinion 20 which may be formed integral with the screw and which is shown as forming a shoulder engaging the under 75 side of the supporting head. An anti-friction washer 21 may be interposed between the shoulder thus provided and the under side of the head and the screw is shown as formed with a spindle extension 22 bearing 80 in a socket provided in the under side of the head.

The driving means for the screw is shown in the form of an operating shaft 23 carrying a bevel gear 24 at its inner end engaging 85 the gear on the screw.

The operating shaft is shown as journaled in a bushing 25 having a reduced cylindrical extension 26 seated in the opening provided in the wall of the sleeve and an outstanding annular flange 27 overlying the outer face of the sleeve and secured thereto by means of a welded joint 28.

The construction disclosed, while relatively light and simple, is very powerful and 105 is small and compact so that it may easily

be carried and handled. A particular feature is the ease with which the device may be made up and assembled. The tubular post is secured to its base and the supporting head is secured in the upper end of the sleeve. The under surface of the supporting head need not be faced off until after it is secured in the sleeve. This insures the provision of a true bearing surface for the 10 shouldered portion of the lifting screw. After the spindle at the upper end of the screw is engaged in its seat, the gear 24 is positioned and engaged on the inner end of the operating shaft, which end may be 15 squared or otherwise shaped to key the gear thereon, the gear being held in position, for instance, by means of a set screw 29.

Provision is made for entering the nut 20 within the sleeve by forming it with recessed or flattened portions 30 at opposite sides thereof, said recesses being of such a depth as to pass the indented or flattened portions at the lower end of the sleeve. After being thus entered in the sleeve, the 25 nut is turned, substantially at right angles in this instance, to bring the outstanding webs thereof into position to stand at opposite sides of the flattened portions of the post, whereupon the nut can be properly 30 seated in the end of the post. In this assembled position, it will be seen that the flattened portions 30 of the nut are out of line with the indented portions of the sleeve and that the remaining portions of the nut 35 which, as shown in Figure 3, are cylindrical, will overstand the indented portions of the sleeve and form a bearing for the sleeve in its sliding movements over the post. These overstanding cylindrical portions, therefore, 40 provide stops for limiting the projection of the sleeve over the post and the anchoring of the nut by the means described, positively prevents the separation of the sleeve from the post.

45 What I claim is:

1. In a jack, the combination with a tubular post having an elongated indented portion, a tubular sleeve slidably engaged over the post and having a short indented portion 50 slidably engaging the indented portion of the post, a nut supported by the post and having a reduced portion movable past the indented part of the sleeve, means for securing the nut to the post with said reduced 55 portion out of line with the indentation of the sleeve, a screw engaged with the nut and connected with the sleeve and means for operating said screw.

2. In a jack, a tubular post, a sleeve slidably engaged over the post, said post and sleeve having portions of reduced diameter 60 slidably engaging to prevent rotation of the sleeve on the post, a screw connected with the sleeve, a nut for said screw supported 65 by the post and having a portion of suf-

ficiently reduced diameter to pass the reduced portion of the sleeve and said nut having a part received in the post and engaging with the portion of lesser diameter to hold the nut with the reduced portion thereof 70 out of line with the reduced portion of the sleeve.

3. In a jack, a tubular post, a sleeve slidably engaged over the post, said post and sleeve having portions of reduced diameter 75 slidably engaging to prevent rotation of the sleeve on the post, a screw connected with the sleeve, a nut for said screw supported by the post and having a portion of sufficiently reduced diameter to pass the reduced portion of the sleeve and said nut having a part received in the post and engaging with the portion of lesser diameter to hold the nut with the reduced portion thereof 80 out of line with the reduced portion of the sleeve and means for securing the nut in such position.

4. In a jack, a tubular post, a sleeve slidably engaged over the post, said post and sleeve having portions of reduced diameter 90 slidably engaging to prevent rotation of the sleeve on the post, a screw connected with the sleeve, a nut for said screw supported by the post and having a portion of sufficiently reduced diameter to pass the reduced portion of the sleeve and said nut having a part received in the post and engaging with the portion of lesser diameter to hold the nut with the reduced portion thereof 95 out of line with the reduced portion of the sleeve and means for securing the nut in such position and comprising a portion of the wall of the post indented into engagement with a shoulder on the nut.

5. In a jack, a tubular post, a sleeve slidably engaged over the post, said post and sleeve having portions of reduced diameter 100 slidably engaging to prevent rotation of the sleeve on the post, a screw connected with the sleeve, a nut for said screw supported by the post and having a portion of sufficiently 110 reduced diameter to pass the reduced portion of the sleeve and said nut having a part received in the post and engaging with the portion of lesser diameter to hold the nut with the reduced portion thereof out of line with the reduced portion of the sleeve and means for securing the nut in such position and comprising a portion of the wall of the post indented into engagement with a shoulder on the nut, the sleeve having an 115 opening therein providing access for a tool for thus indenting the post into engagement with the nut.

6. In a jack, a tubular post having flattened sides, a sleeve slidably engaged over the post, said sleeve having short indented portions near one end arranged to cooperate with the flattened sides of the post, a lifting head affixed to the other end of the 120 125 130

sleeve, a screw connected with the sleeve, and a nut for the screw, said nut having a part of greater diameter than the inside diameter of the post, adapted to rest on the top of the post, opposite portions of said post being flattened to clear the indented portions of the sleeve, and a part received in the post and engaging with the flattened sides thereof to hold the nut with its flattened portions out of line with the indented portions of the sleeve.

In witness whereof, I have hereunto set my hand, this 23rd day of March, 1920.

MALCOLM D. RIKER.
